(57) **CLAIM**

The ornamental design for a light fixture, as shown and described.

DESCRIPTION

FIG. 1 is a perspective view of a light fixture showing my new design;

FIG. 2 is a bottom view thereof;

FIG. 3 is a front view thereof; and,

FIG. 4 is a right side view thereof, a left side view being a mirror image thereof.

The broken lines shown in the drawings illustrate portions of the light fixture that form no part of the claimed design.
